US0D1001699S

(12) **United States Design Patent** (10) **Patent No.:** **US D1,001,699 S**
(45) **Date of Patent:** **** Oct. 17, 2023**

(54) **VEHICLE FENDER FLARE**

- (71) Applicant: **Bushwacker, Inc.**, Buford, GA (US)
(72) Inventor: **Brent Lorenz Rose**, Jefferson, GA (US)
(73) Assignee: **Bushwacker, Inc.**, Buford, GA (US)
(**) Term: **15 Years**
(21) Appl. No.: **29/751,526**
(22) Filed: **Sep. 22, 2020**

Related U.S. Application Data

- (63) Continuation of application No. 29/668,021, filed on Oct. 26, 2018, now Pat. No. Des. 898,640.
(51) **LOC (14) Cl.** **12-16**

(57) **CLAIM**

The ornamental design for a vehicle fender flare, as shown and described.

DESCRIPTION

FIG. 1 is a front perspective view of an embodiment of a vehicle fender flare;

FIG. 2 is a bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

Broken lines are used to illustrate features of the vehicle fender flare which form no part of the claimed design. Dash-dot lines indicate a boundary of claimed subject matter.

1 Claim, 7 Drawing Sheets
